UNITED STATES PATENT OFFICE.

FREDERICK C. SPENCER, OF GUILFORD, CONNECTICUT.

LIFTING-JACK.

1,175,569.

Specification of Letters Patent. Patented Mar. 14, 1916.

Application filed September 15, 1915. Serial No. 50,763.

To all whom it may concern:

Be it known that I, FREDERICK C. SPENCER, a citizen of the United States, and resident of Guilford, in the county of New Haven 5 and State of Connecticut, have invented a new and useful Improvement in Lifting-Jacks, of which the following is a specification.

My invention relates to an improvement 10 in lifting jacks with the object in view of providing means for preventing the backward movement of the pinion nut when the operating lever is swung back.

A practical embodiment of my invention 15 is illustrated in the accompanying drawings, in which,

Figure 1 is a view of the jack in side elevation, the operating lever being shown in full lines out of operative position, and in 20 dotted lines in operative position. Fig. 2 is a vertical central section, Fig. 3 is a transverse section in the plane of the line A—A, Fig. 1, and Fig. 4 is a transverse section in the plane of the line B—B, Fig. 1.

The general construction of the jack is 25 quite similar to the structure of the jack shown, described and claimed in Letters Patent No. 1,148,868, granted to me on the 3rd day of August, 1915, and need not be 30 particularly described herein.

The pedestal is denoted by 1, the pawl carrying ring mounted on the pedestal by 2, the double-acting pawl by 3, the lifting screw by 4, the pinion nut engaged with the 35 screw by 5, and the operating lever suspended from the pawl carrying ring 6.

It has been found in practice necessary to hold the pinion nut 5 with one hand, against 40 a return movement while the other hand was working the operating lever, until such time as the weight on the lifting screw produced sufficient friction to hold the nut. This use of both hands on the jack when the body of the operator is in the awkward or cramped 45 position commonly assumed under a motor car, is inconvenient and annoying and it is to remedy this inconvenience and annoyance that my present invention is made.

The pedestal 1 is provided conveniently

on the side opposite that on which the operating lever is normally located, with an upwardly extending arm 7. At a point opposite the teeth on the nut 5, the arm 7 is provided with a bore 8 in which is freely mounted a dog 9, the inner end of which is 55 in position to engage the teeth on the nut 5, and the outer end in position to be pressed upon by the free end of a spring strip 10, secured at its lower end to the arm 7, in the present instance by a screw 11. The dog 9 is 60 preferably made cylindrical so that it may rotate freely in the bore 8, as well as slide longitudinally therein, and its inner end is made in a blunt conical shape so that it will present the same degree of inclined obstruction 65 to the teeth of the nut, whatever be its rotary adjustment in its bore. This will prevent the dog from irregular wear as it will be free to present a new surface to the teeth at each step of rotation of the nut. The 70 spring tension on the dog is intended to be just sufficient to prevent a backward movement of the nut when the lever is returned for a new stroke, and the dog will slide over the teeth of the nut as the nut is forcibly 75 turned by the operating lever.

With this construction only one hand of the operator is required to operate the jack even before the weight of the object to be lifted is exerted on the jack and its practical efficiency is thereby materially improved.

What I claim is:

1. In combination with a pinion nut, a lifting screw with which the nut is engaged, a support for the nut and means for operating it, a yielding dog having a tapered end in position to engage the teeth on the pinion nut to hold it against an unintentional backward movement while permitting it forced movement. 85

2. In combination with a pinion nut, a lifting screw with which the nut is engaged, a support for the nut and means for operating it, a longitudinally yielding rotary dog having a tapered end in position to engage 95 the teeth of the nut to prevent unintentional movement of the nut while permitting intentional movement of the same. 90

3. In combination with a pinion nut, a lifting screw with which the nut is engaged, a support for the nut provided with an arm extending upwardly therefrom; the said arm provided with a bore opposite the nut, and means for operating the nut, a rotary dog seated in the bore in the arm and a

spring for forcing the dog into engagement with the teeth of the nut.

In testimony that I claim the foregoing 10 as my invention, I have signed my name this 4th day of September, 1915.

FREDERICK C. SPENCER.
